UNITED STATES PATENT OFFICE

2,366,764

RETAINER FOR PARACHUTE SHROUD LINES

Harry Wilson, Dayton, Ohio

Application July 26, 1943, Serial No. 496,225

2 Claims. (Cl. 244—148)

(Granted under the act of March 3, 1883, as amended April 30, 1928; 370 O. G. 757)

The invention described herein may be manufactured and used by or for the Government for governmental purposes, without the payment to me of any royalty thereon.

This invention pertains to retainers for packets of bights of shroud lines of a parachute, the primary object of which is to compressionally hold the bights of the lines to prevent entanglement of the unfurled portions as the lines pay out.

This invention is an improvement of the type disclosed in United States Patent No. 1,774,513, which includes a plurality of spaced pockets disposed diametrically opposite one another on the inner face of the back of the pack for receiving the looped portions of the sinuously disposed shroud lines. The type of shroud line pockets disclosed in the foregoing patent, as well as in United States Patents No. 1,554,192 and No. 2,026,314, has little or no holding effect on the bights of the lines except for the compression created by tucking the pockets full. When one or two shroud line folds are unfurled from a given pocket, the remaining bights of that packet are freed, and may cause serious entanglement, because the cross-sectional area of the pockets remain substantially constant.

An aim of the present invention is to compressionally grip the bights of the shroud line packet, as they are successively reduced in number during the pay out, by providing elastically distortive retaining pockets.

These and other objects of the invention will become apparent from the following specification, appended claims, and the accompanying drawings illustrating certain embodiments having the characteristics of my invention and by which the same may be practiced.

Fig. 1 is a schematic perspective of an open parachute pack illustrating the application of the improved shroud line packet retainers and the arrangement of the shroud lines therein.

Fig. 2 illustrates the manner in which the parachute pack is worn and in which position the improved shroud line retainers are stretched into maximum holding position, as shown in Fig. 5.

Fig. 3 is an enlarged section in perspective, illustrative of the improved retainers slackened for loading of the shroud line bights.

Fig. 4 is a sectionalized view illustrative of the unloaded retainer under tension.

Fig. 5 is a perspective view of the loaded retainer sectionalized to illustrate the shape of the retainer loops when under tension across the back of the wearer.

Figs. 6, 7 and 8 are enlarged sections of embodi-

ments of my invention illustrating the use of different materials.

The present invention is intended for use in connection with non-rigid, frameless parachute 5 packs of the character illustrated in Fig. 1 and consists of a pair of strap-like members 10 and 11 disposed across the inner face of the back panel 12 of the parachute pack and at the opposite ends thereof. Each of the strap-like members are formed by a pair of superimposed strips of material 13 and 14 secured together at their ends 15 and 16 and at spaced intervals 17 to provide spaced passageways 18 which may be opened to loop formations 19 as shown in Fig. 3 or drawn 15 to slit formation 20 as shown in Fig. 4, or drawn down upon the shroud line bights as shown in Fig. 5.

At least one of the strips 13 and 14 of each of the strap-like members 10 and 11 is of elastic 20 material. In the embodiment illustrated in Fig. 7, the bottom strip 14 is of rubber or of expansible fabric interwoven with rubber threads, whereas the upper strip 13 is of the non-elastic character such as canvas, leather, etc. In the embodiment 25 of Figs. 3, 4 and 5, however, both strips 13 and 14 are of rubber or rubber-like material. In lieu of rubber, both strips may be of expansible fabric interwoven with elastic threads as illustrated in Fig. 6.

30 The strips 13 and 14, as secured together to form the loop-provided strap-like members 10 and 11, are stretched at least to the point at which the loop formations are substantially closed or to the point at which the respective strips of a strap-like member are brought substantially into parallelism, as shown in Fig. 4, and are thence secured at their ends 15 and 16 to the inner face of the back 12 of the pack. The portions of the strap-like members intermediate the secured ends 35 are unsecured and free to contract and open the passageways 18 into loop formations 19 as shown in Fig. 7; free to be slackened to open the passageways as shown in Figs. 3 and 6; and free to be stretched back into parallelism when the portions 40 of the back of the pack between the points of securing of the respective straps are made taut, as shown in Fig. 4 and in dotted lines in Fig. 7.

In the embodiment illustrated in Fig. 8, the back 12 of the parachute pack is utilized as an 45 equivalent for the bottom strip 14 of the embodiment illustrated in Figs. 1 through 7. In this embodiment, the strip 13 is secured at the intervals 17 directly to the back of the pack.

In packing the shroud lines, the back 12 of the 50 pack is slackened, as shown in Figs. 3 and 6 or

permitted to be drawn slack by the strap as by the embodiment of Fig. 7, sufficiently to allow the strap passageways 18 to be distended or opened to readily permit the packets of shroud lines 21 to be drawn into the loops 19. When the loaded pack is placed upon the back of a wearer, the back 12 of the pack is subjected to sufficient tension or pull as to remove practically all of the slack required to distend the strap passageways, and in doing so the elastic strips of the straps are stretched, causing the loop 19 to be drawn down oval-wise and compressionally grip the packet of shroud line bights. As the bights are successively drawn or payed out, the tension on the back of the pack and elasticity of the loop forming strips continue to reduce the capacity of the loops, whereby the holding effect continues down to the last bight.

Having described my invention and illustrated an embodiment by which the same may be practiced, what I claim is:

1. Shroud line retaining means of a parachute

pack comprising strips of elastic material secured together in superimposed relationship at spaced intervals and secured at their ends to a member of said parachute pack at points sufficiently removed from one another to cause said strips to be drawn into substantial parallelism when said parachute pack member is drawn taut.

2. A parachute pack having spaced rows of loops expansible to receive and automatically contractible to compressionally hold bights of shroud lines, wherein the rows of loops are formed of superimposed strips, the upper one of which is secured in a corrugated manner at spaced intervals to the lower-most member of said superimposed strips, wherein the lower-most strip is of elastic material, and wherein said superimposed strips are secured at their ends to a member of the parachute pack at points removed from one another a distance substantially equal to the length of the upper-most of said superimposed strips when drawn taut.

HARRY WILSON.
